Primary Examiner — Brett Miller*Assistant Examiner* — Rani J Abdallah(74) *Attorney, Agent, or Firm* — William Thomas Babbitt;
Leech Tishman Fuscaldo & Lampl(57) **CLAIM**

The ornamental design for a bottle, as shown and described.

DESCRIPTION

FIG. 1 is a perspective view of a bottle;

FIG. 2 is a plan view of the top of the bottle;

FIG. 3 is a plan view of the bottom of the bottle;

FIG. 4 is a plan view of a first side of the bottle;

FIG. 5 is a plan view of a second side of the bottle;

FIG. 6 is a plan view of the front side of the bottle; and,

FIG. 7 is a plan view of the rear side of the bottle.

The broken lines depict portions of the bottle that form no part of the claimed design.

1 Claim, 4 Drawing Sheets(56)
